UNITED STATES PATENT OFFICE.

THOMAS H. SEELY, OF MALDEN, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

SPEED-CHANGING MECHANISM.

1,348,902.

Specification of Letters Patent. Patented Aug. 10, 1920.

Application filed December 28, 1916. Serial No. 139,378.

To all whom it may concern:

Be it known that I, THOMAS H. SEELY, a citizen of the United States, residing at Malden, in the county of Middlesex and State 5 of Massachusetts, have invented certain Improvements in Speed-Changing Mechanism, of which the following description, in connection with the accompanying drawings, is a specification, like reference characters on the drawings indicating like parts in the several figures.

The invention to be hereinafter described relates to variable-speed mechanism, and more particularly mechanisms of this type 15 adapted for use in machines for manufacturing boots and shoes.

Ordinarily, the speed at which a boot or shoe making machine is intended to be operated is the same for all portions of the 20 work treated by it, and is governed usually by the capacity of the operator properly to present the work to the machine. In lasting machines, for instance, where the different parts of the upper about the shoe are 25 successively worked into lasting position, the speed at which the machine may be advantageously run, will depend upon the rapidity with which the operator can successively present the different portions of 30 the shoe properly to the lasting devices. While lasting the shank, sides, and toe of a shoe, pincer mechanism is usually employed to seize, pull and lay successive portions of the upper materials over the innersole, but 35 while passing about the heel seat it is not necessary to thus pull the upper owing to the shape of the last at this portion of the shoe, so the operator "dodges" the pincers at each pincer movement about the heel seat, 40 that is, he slightly tilts or shifts the shoe as the pincers seek to grip the upper materials, and the upper is laid into lasting position at such times by the wiper or presser. Thus 45 about the heel seat it is possible for the operator more rapidly to present the shoe properly to the lasting devices than along the other portions of the shoe, but if the machine maintains the same speed of operation while treating the shoe about the heel seat 50 as it does while treating the other portions of the shoe, it is not working to the best advantage and much valuable time is lost.

Accordingly, one of the objects of the present invention is to provide a novel and

improved speed changing mechanism constructed and arranged to enable the operator to run the machine at one speed while successively working the upper of a shoe to lasted position along the shank, sides, and toe and at a different speed while lasting 60 about the heel seat. To attain this and other objects of the invention it is important that the speed changing mechanism shall be quickly responsive to the will of the operator, and an important feature of the present 65 invention, therefore, consists of a driving member and a single driven member operatively connected to the main shaft of the machine, and positively acting means between the driving and driven members controllable 70 at will for positively operating the driven member at different speeds from the driving member.

Another object of the invention is the production of a speed controlling means 75 having provision for the positive transmission of speed from the driving to the driven member wherein the parts are combined for more efficient and reliable operation than heretofore. Another important feature of 80 the invention, therefore, consists in a clutch member for operatively connecting the driving and driven members and two gears, which under control of the operator, may be readily caused to rotate about a common 85 center for operating the driving and driven members at the same speed or about different centers for increased speed of the driven member. To attain these and other objects, the invention in its preferred form comprises an internally toothed gear which, 90 when the driving and driven members are operatively connected by the clutch member, rotates with and at the same speed as the driving member, and an externally toothed 95 gear of less number of teeth connected to rotate with the driven member and meshing with the internally toothed gear, and manually controlled means for locking the two gears from relative rotation that the driven 100 and driving members may rotate at the same speed, and for freeing them to relative rotation that the speed of the driven member may be increased.

The various features of the invention 105 above referred to and other features and advantages thereof will more fully and clearly appear from the following descrip-

tion of the invention read in connection with the accompanying drawings which illustrate one good practical form or embodiment thereof. The invention will be herein exploited as applied to that type of lasting machine wherein the upper materials are worked to lasted position by successive operations of the lasting devices at different portions of the upper, and while the present invention has special adaptation for that type of shoe making machine, it is not to be understood as limited thereto but may be employed with advantage in other types of machines.

15 In the drawings:—

Figure 1 is a side elevation and part sectional view of a speed changing mechanism containing the present invention, and operatively connected to the main shaft of a lasting machine;

20 Fig. 2 is an enlarged end view looking from the left of Fig. 1, some of the parts being broken away and others shown in section to make clear their association and relation;

25 Fig. 3 is an enlarged cross-section on the line 3—3 of Fig. 1, some of the parts being broken away to more clearly disclose the construction and connection of parts beyond.

30 The machine to which the present invention is applied by way of illustration, comprises a base frame 1 from which rises a column or standard for supporting the main shaft 2 of the machine by which the working tools, such as the pincers and associated parts, are actuated. These tools and their relation to the main shaft 2 are not herein illustrated and described, as they are well understood by those skilled in the art, and 35 the particulars thereof do not form essentials of the present invention.

40 Rising from the base frame 1 are the arms 3, 3, provided with a suitable support for the driving member of the speed changing mechanism. In the present instance of the invention the support comprises a shaft 5 sustained in bearings 4, 6 and having mounted thereon the driving member 7, which may be continuously driven from a 45 prime motor or suitable source of power to which it may be operatively connected, as by the belt 8. The driven member 9 of the speed changing mechanism is loosely sustained by the shaft 5, and is operatively connected to the main shaft 2 of the machine as by the belt 10, substantially as illustrated in Fig. 1, the construction being such that the single driven member 9 will transmit its movement of rotation to the main shaft of 50 the machine.

55 The present invention contemplates a clutch member for operatively connecting the driving and driven members, and speed changing elements for effecting different 60 speeds of the driven member 9 from the

uniform speed of the driving member 7. In the present instance of the invention the clutch member comprises a disk 11 having a flange 12 which may be faced with some frictional material, such as leather or the like 13 for engaging frictionally with a similar flange 14 projecting from the driving member, the essentials in these respects being that the driving and driven members of the speed changing mechanism may be 75 operatively connected and disconnected.

65 The friction member 11 has an elongated sleeve or hub portion 15 loosely mounted upon the shaft 5, and preferably provided with suitable lubricating ducts, as shown. 80 In order that the friction member may be appropriately moved to operatively connect or disconnect the driving and driven members at will, suitable means are provided under treadle control for moving the sleeve 85 15 longitudinally of the shaft 5. In the present instance of the invention a collar 16 is loosely mounted upon the shaft 5 and is moved longitudinally thereof by a wedge 17 under suitable manual control, a good 90 form of such control being illustrated by Fig. 1, wherein, a treadle operated element or lever 18 is pivotally connected at 19 to a slide member 20 adapted for movement transversely of the shaft 5, and having pivoted thereto at 21 a bell crank 22, one portion of which is connected by a link 23 to the wedge 17, and the other end of which is yieldingly held by a pin 24 passing through the end of the bell crank and slide member 95 20 and normally under the action of a spring 25, surrounding the pin 24. The action of the spring is adjustably restricted by the head 26 of the pin and the adjustable nut 27, the construction being such that upon 100 depression of the treadle the slide 20 will be raised carrying with it the wedge 17 and thereby moving the collar 16 longitudinally of the shaft 5 to place the clutch member 105 in operative connection with the driving 110 member, and upon further depression of the treadle, the yieldingly mounted bell crank 22 will permit the slide further upward movement without corresponding movement of the wedge 17.

115 The collar 16 may be connected to the sleeve or hub 15 in some cases, as by means of a collar 28 secured to the sleeve or hub by a set screw 29 or other device, and joined to the collar 16 by an arm 30. If desired, a 120 washer 31 may be loosely interposed between the collars 16 and 28 or between the collar 16 and the end of the sleeve 15, the construction being such that movement of the collar 16 to the right, Fig. 1, will effect corresponding 125 movement of the clutch member to operatively connect the driving and driven members of the speed changing mechanism and movement of the collar 16 to the left will effect corresponding movement of the 130

- clutch member to operatively disconnect the driving and driven members. Movement of the collar 16 to operatively disconnect the driving and driven members may 5 be accomplished in various ways, but in the present instance, a spring 32 has one end connected to the collar 16, as by the pin 33, and its other end connected to a fixed part, such as the bearing 6 by a similar pin 34.
- 10 Loosely mounted upon the sleeve 15 and extending between the collar 28 and the disk 11 of the clutch member is the sleeve 35 carrying an eccentric portion 36, which in the present instance of the invention, is 15 arranged between the driven member 9 and the disk 11 of the clutch member. An externally toothed ring or gear 37 is loosely mounted upon the eccentric portion 36 of the sleeve 35 and is operatively connected 20 to the driven member 9 to rotate therewith. In the present instance of the invention, this connection is effected by a link 38, one end of which is secured to the driven member 9 by a pin 39 and the other end of which 25 is secured to the externally toothed gear 37 at 40, Fig. 3, the construction being such that motion imparted to the externally toothed gear 37 will be directly transmitted to the driven member 9.
- 30 The externally toothed gear 37 is operatively connected to an internally toothed gear 41 preferably as shown, by intermeshing relation of the teeth of the respective gears. The internally toothed gear 41 has a 35 larger number of teeth than the externally toothed gear 37, and when the driving and driven members of the change speed mechanism are operatively connected, the internally toothed gear 41 rotates with and at 40 the same speed as the driving member 7. This is effected in the present instance of the invention by mounting the gear 41 on the clutch member as by means of the pins 42.
- 45 The present invention contemplates that during normal machine operation, the driving and driven members shall rotate at the same speed and that the speed of the driven member may be increased at times under 50 the control of the operator. To these ends, means are provided under the control of the operator for causing the internally and externally toothed gears to rotate about a common center without relative rotation 55 when the driving and driven members are to be operated at the same speed and to free them to relative rotation about different centers when the speed of the driven member is to be increased. In carrying this feature 60 of the invention into effect, in the present instance of the invention the sleeve 35 is provided with a flange 43, which is preferably secured thereto by a clamping bolt 44, Fig. 2, passed through portions 45 of the 65 flange, the construction being such that while the flange is caused to rotate with the sleeve 35 carrying the eccentric 36, it may slip to some extent thereon to absorb the shock incident to stopping rotation of the eccentric carrying sleeve 35, as will more 70 fully appear. To prevent movement of the flange 43 longitudinally of the sleeve, the flange has secured thereto a lug 46, the end of which engages a groove 47 formed in the sleeve 35, substantially as indicated in 75 Fig. 1.
- Between the flange 43 and the driven member 9 is means under control of the operator for connecting or disconnecting the flange and, perforce, the eccentric carrying 80 sleeve 35, for rotative movement with or independent of the driven member. In the present instance of the invention, this means consists of a latch 49 pivoted at 50 to the flange 43, Fig. 2, and provided with a locking shoulder 51, which, under the impulse of a spring 52 is normally held in engagement with a recess 53 on the driven member 9, the construction being such that when the shoulder 51 and recess 53 are engaged 90 the flange 43 and driven member 9 are locked for rotative movement together. Under the conditions described, it will be noted that the eccentric 36 will rotate with the driven member and the internally and externally toothed gears will rotate together 95 about a common center 54 and be locked from relative rotation.
- The recess 53 is preferably formed in a plate 55 secured to the driven member 9, 100 as indicated in Fig. 1, although, obviously, it may be otherwise contrived.
- The latch 49, Fig. 2, is also provided with a recess adapted to be engaged by a controller or stop 57 secured to the slide 20, 105 Fig. 1, the construction being such that when the treadle is depressed normally for operating the driving and driven members at the same speed, the controller or stop 57 is not raised sufficiently to engage the latch 110 49, but upon further depression of the treadle, the controller or stop 57 is lifted to engage the latch as the latter is carried about the shaft 5 with the flange 43 and driven members, thereby first lifting the 115 latch to unlock the connection between the flange 43 and driven member and then to engage the recess 56 of the latch to stop rotation of the flange and eccentric carrying sleeve 35. When the controller or stop 120 57 is thus raised into engagement with the recess 56 of the latch the eccentric carrying sleeve is held stationary and the internally and externally toothed gears then rotate relatively about their respective centers 54 125 and 58, Fig. 3. Since the numbers of teeth in the internally toothed gear is greater than the number of teeth in the externally toothed gear, the latter will be rotated at an increased speed from the internally toothed 130

gear and performe transmit such increased speed to the connected driven member 9.

When the treadle is thus further depressed to lift the controller 57 into locking engagement with the latch 49, the bell crank 22 connected to the wedge 17 is caused to turn about its pivotal connection 21 with the slide 20 against the expansive action of the spring 25.

- 10 In order that the controller may act in the sequential order stated, that is, lift the latch from locking engagement with the driven member and engage the recess 56 of the latch, the latter is preferably formed 75 with an inclined end portion 59, Fig. 2, which may ride over the end of the controller 57 when the latter is additionally raised and then under the action of the spring 52 drop into locking engagement 80 therewith.

It may sometimes be desirable to provide for lubrication of the externally toothed gear, and to this end the eccentric carrying sleeve 35 may be provided with an oil duct 25 60 leading to an absorbent pad 61 such as felt, seated in a radially formed opening in the eccentric 36.

What is claimed is:—

1. A speed changing mechanism having a 30 driving member, a driven member, a clutch between said driving and driven members, manual means movable to operate the clutch to cause the driven member to be driven from the driving member at the same speed, 35 and connections between the clutch and the driven member to drive the driven member at another speed, said connections being normally inoperative and constructed and arranged to be rendered operative by further 40 movement of the manual means in the same direction.

2. In a machine of the character described, the combination of a main shaft, a driving member, a single driven member operatively 45 connected to said shaft, gearing connections between the driving and driven members including a clutch, and means for locking the gearing connections from relative movement to cause the driving and driven members to move at the same speeds and operable at will for freeing the gearing connection to relative movement to impart increased speed to the driven member from the driving member.

- 50 3. In a machine of the character described, the combination of a driving member and a single driven member, a clutch device between said members, manually operated means for actuating the clutch device, means 55 between the clutch device and one of said members for transmitting the movement of the driving member at different speeds to the single driven member when the members of the clutch device are operatively engaged, 60 and devices controlled from said manually

operated means for determining the speed transmitted to the single driven member.

4. A speed changing mechanism having a driving member, a driven member, a clutch between said driving and driven members, 70 manual means movable to operate the clutch to cause the driven member to be driven from the driving member at one speed, connections between the clutch and the driven member to drive the driven member at another speed, and means operated by further movement of the manual means in the same direction constructed and arranged to cause said connections to drive the driven member at the other speed. 75

5. A speed changing mechanism having, in combination, a driving member, a driven member, a clutch device between the driving and driven members, a gear movable with the driving member when the members 80 of the clutch device are operatively connected, a gear connected to the driven member, means for normally locking said gears from relative movement to cause the driven and driving members to move at the same speed, and means for freeing the gears to relative movement to cause the driven member to move at a higher speed than the driving member. 85

6. A speed changing mechanism having, 90 in combination, a driving member, a driven member, a clutch device between the driving and driven members, an internally toothed gear movable with the driving member when the members of the clutch device are 100 operatively connected, an externally toothed gear meshing with the internally toothed gear and connected to the driven member to rotate therewith, means for locking said gears from relative rotation for driving the 105 driven member at the same speed as the driving member, and means operable at will for tripping the locking means for freeing the gears to relative rotation to cause the driven member to rotate at a different speed 110 than the driving member.

7. A speed changing mechanism comprising, in combination, a driving member and a driven member, a clutch device between said members, an internally toothed gear 115 movable at the same speed as the driving member when the members of the clutch device are operatively connected, an externally toothed gear having a less number of teeth than the internally toothed gear and 120 meshing therewith, connections between the externally toothed gear and the driven member to cause them to move at the same speed, means for causing the internally and externally toothed gears to rotate together 125 without relative rotation, and manually controlled means for freeing them to relative rotation for increasing the speed of the driven member.

8. A speed changing mechanism, compris- 130

- ing, in combination, a driving member and a driven member, a clutch device between said members, a gear connected to a member of the clutch device to rotate therewith, 5 a smaller gear connected to rotate with the driven member and meshing with the larger gear, means for causing the two gears to rotate together without relative rotation for driving the driven member at the same 10 speed as the driving member, and manually controlled means for freeing the gears to relative rotation that the driven member may be rotated at a different speed than the driving member.
- 15 9. In an apparatus of the class described, the combination of a driving member and a driven member, a clutch member interposed between the driving and driven members, manually movable means for operatively connecting the clutch member and the driving member, gearing connections between the clutch member and driven member, means for locking the gearing from relative rotation to cause the driving and 20 driven members to operate at the same speed, and a device for freeing the gearing to relative rotation at will that the driving and driven members may rotate at different 25 speeds.
- 30 10. A speed changing mechanism, comprising, in combination, a driving member and a driven member, a clutch device between said members, intermeshing eccentrically mounted gears between the clutch 35 device and driven member, and manually controlled means for causing said gears to rotate about a common center that the driving and driven members may be operated at the same speed, and means for causing 40 said gears to rotate about different centers that the driving and driven members may rotate at different speeds.
11. A speed changing mechanism, comprising, in combination, a driving member 45 and a driven member, a clutch device between said members, an internally toothed gear movable with the driving member when the members of the clutch device are operatively connected, an eccentrically 50 mounted externally toothed gear meshing with the internally toothed gear and connected to the driven member for rotation therewith, and means for causing the two 55 gears to rotate about a common center without relative rotation that the driving and driven gears may rotate at the same speed and for causing them to rotate about separate centers that the driven and driving members may be rotated at different speeds.
- 60 12. In a speed changing mechanism, the combination of a driving member and a driven member, a clutch member between the driving and driven members, two eccentrically mounted gears one connected to the 65 clutch member and the other to the driven member, and manually controlled means for causing said gears to rotate together about a common center that the driving and driven members may be operated at the same speed and for causing them to rotate relatively about different centers that the driving and driven members may operate at different speeds.
- 70 13. In an apparatus of the class described, the combination of a driving member, a driven member, a clutch member, manually controlled means for moving the clutch member to operatively connect it with the driving member, an internally toothed gear movable with the driving member when the 75 driving and clutch members are operatively connected, an eccentric, an externally toothed gear meshing with the internally toothed gear and mounted on said eccentric, connections between the driven member and 80 the externally toothed gear to cause them to move together, locking means for causing the internally and externally toothed gears to rotate together about a center concentric with the internally toothed gear, and a device 85 for tripping the locking means to free the externally toothed gear to turn about a center eccentric to the internally toothed gear.
- 90 14. A speed changing mechanism, comprising, in combination, a driving member and a driven member, means between said members for transmitting variable speeds from the driving to the driven member including a clutch and two gears, one an internally toothed gear and the other an externally toothed gear meshing with the internally toothed gear, an eccentric carrying the externally toothed gear, a link connecting the externally toothed gear and driven 95 member, means for normally locking said gears from relative rotation to transmit one speed from the driving to the driven member, and means for tripping the locking means to permit the gears to rotate relatively 100 for the transmission of a different speed from the driving member to the driven member.
- 105 15. In a speed changing mechanism, the combination of a driving member and a driven member, an eccentric, means normally acting to lock the driven member and eccentric for rotation in unison, an externally toothed gear mounted on the eccentric and connected to the driven member, a clutch 110 member adapted to be driven by the driving member, an internally toothed gear rotatable with the clutch member and meshing with the externally toothed gear, means for locking the externally toothed gear from rotation relative to the internally toothed gear for the transmission of one speed, and means for freeing the externally toothed gear to such relative rotation when a different speed 115 is desired.
- 120 125 130

16. In a speed changing mechanism, the combination of a driving member and a driven member, and means between said members for transmitting variable speeds from the driving to the driven member including a clutch and intermeshing eccentrically-mounted gears between the clutch and driven member, means normally acting to cause said eccentrically mounted gears to be rotated together without relative rotation for the transmission of one speed to the driven member; and means for freeing the gears to relative rotation for the transmission of a different speed.
17. A speed changing mechanism, comprising, in combination, a driving member and a driven member, an eccentric, means for normally locking the eccentric and driven member for rotation in unison, a gear mounted on the eccentric and connected to the driven member, a clutch member carrying a gear having a greater number of teeth than the eccentrically-mounted gear and in mesh therewith, means for operatively connecting the clutch member and driving member, and means under control of the attendant for unlocking the eccentric from the driven member and holding the eccentric from rotation.
18. A speed changing mechanism, comprising, in combination, a driving member and a driven member, an eccentric carrying an externally toothed gear, means for connecting the externally toothed gear and driven member, a latch for normally locking the eccentric and driven member for rotation in unison, a clutch member, means operable at will for connecting the clutch member and driving member, an internally toothed gear carried by the clutch member and meshing with the externally toothed gear, and means operable at will for tripping the latch and freeing the eccentric from rotation with the driven member.
19. A speed changing mechanism, comprising, in combination, a driving member and a driven member, an eccentric carrying a toothed gear that is connected for rotative movement with the driven member, a clutch member carrying a gear intermeshing with the eccentrically-mounted gear, means for operatively connecting at will the clutch member and driving member, means for locking the eccentric to the driven member to cause the two gears to rotate at the same speed about a common center, and means for freeing the eccentric from rotation with the driven member and locking it from rotation that the gears may rotate about different centers when high speed is desired.
20. A speed changing mechanism, comprising, in combination, a driving member and a driven member, an eccentric carrying a toothed gear that is connected for rotative movement with the driven member, a clutch member carrying a gear intermeshing with the eccentrically mounted gear, means for operatively connecting at will the clutch member and driving member, a latch normally locking the eccentric to the driven member to cause the two gears to rotate about a common center without relative rotation, and attendant-controlled means for tripping the latch and holding the eccentric from rotation that the gears may rotate about different centers at different speeds.
21. A speed changing mechanism having a driving member, a driven member, a clutch between said driving and driven members, manual means for operating the clutch to cause the driven member to be driven directly from the driving member at the same speed, normally inoperative geared connections between the clutch and the driven member for operating the driven member at another speed, and means rendered operative by further movement of the manual means in the same direction for causing the driven member to be operated through said geared connections.

In testimony whereof I have signed my name to this specification.

THOMAS H. SEELY.
